UNITED STATES PATENT OFFICE.

ELLIOTT E. FURNEY, OF ST. LOUIS, MISSOURI.

APPARATUS FOR CHECKING THE WASTE OF WATER.

SPECIFICATION forming part of Letters Patent No. 244,882, dated July 26, 1881.

Application filed March 24, 1881. (Model.)

To all whom it may concern:

Be it known that I, ELLIOTT E. FURNEY, of the city of St. Louis, in the State of Missouri, have invented certain new and useful 5 Improvements in Apparatus for Checking the Waste of Water, of which the following is a full, clear, and exact description, reference being had to the accompanying drawings making part of this specification.

10 My present invention is an improvement on my patents dated, respectively, September 21, 1880, and January 4, 1881.

The improvements are set forth in the claims.

15 Figure 1 is an axial section of the apparatus, showing the position of the parts just after the closing of the discharge-cock. Fig. 2 is a similar section, showing the position of parts while the water is flowing. Fig. 3 is a 20 diagram in section, showing a modification.

A is the receiving end of the apparatus, connected with the city main, or with some other source of supply of water under pressure.

B is the induction-cock, or a cock in the induction-pipe A. The pipe A discharges into the lower end of the case C through a passage, c, across which, in Fig. 1, is a bar, D, carrying a pin, d, whose purpose is to clear the small water-orifice e in the disk-valve E. I prefer 30 to make the clearing-pin d long enough to extend into or through the orifice e when the disk-valve is in its upper position, the pin being made to loosely fit the hole e, so that the water would flow through the hole around the 35 pin. In Fig. 2 is shown a modification in which the clearing-pin d projects from the bottom of the piston H. In this arrangement the pin would pass into the hole e at each descent of the piston. The valve E is raised by the 40 influx of water when the discharge-valve is opened, and descends by gravity when the flow is arrested and the orifice e is kept open by the pin. (See Fig. 1.) The valve E plays in the lower portion, F', of a vertically-moving cylinder, F, said portion being below the 45 deep circumferential groove G, which groove forms in the cylinder a neck, G', through which the water passes upward to lift the automatic valve H I, and through which it passes 50 downward as the piston part of said valve descends. The cylinder F works against the

ends of guide-screws J screwed through the sides of the case C, and bearing so lightly against the sides of the cylinder as to allow its free vertical movements. The valve-piston H 55 works (as a piston) inside the cylinder F from the neck G' to the upper end of the cylinder. The piston has in its top a cup, H', which receives a ball-valve, I, detached from the piston H, so that the piston commences its descent at 60 the moment the ball-valve reaches its seat K and closes the eduction-passage L. As the valve I closes the eduction-passage the excess of pressure beneath the piston ceases, and the pressure above and below the piston H, cylinder F, and valve E is equalized, causing them to descend, owing to their being of greater specific gravity than water. The ball-valve I does not fit tightly in the piston-cup, so that the water has access to the under side 70 of the ball I through an orifice, h, or otherwise, and there is no impediment to the piston leaving it against its seat. The ball-valve will remain closed against its seat as long as the discharge-cock L' in the eduction-pipe L remains 75 open, (or until the induction-cock B is closed,) and thus prevent the escape of any water, except the little that passes through the small orifice l, extending from the chamber in case C to the eduction-pipe L above the valve; but immediately on the closing of the discharge-valve (or the induction-valve) the pressure on the upper side of the ball-valve becomes equal to that below it, and the ball-valve descends from its seat. The cock or valve L' may be 80 immediately reopened, and the flow will not be again checked by the automatic valve until the piston has had time to make its ascent in the cylinder F and carry the ball-valve up to its seat. 90

I have shown a ball-valve, I, as the best form of detached valve; but I do not confine myself to this form of valve, but claim any valve closed by the automatic piston and capable of keeping the eduction-passage closed in the descent 95 of the piston H. The closing of the operating-cock B would act on the automatically-moving valve apparatus in substantially the same manner as closing the cock L' in the discharge-pipe L—say of an ordinary hydrant having my apparatus applied thereto; for when the passage of water is stopped the hydraulic pressure will 100

cease and the valve apparatus would gravitate. When there is an operating-cock, B, in the induction-pipe, a small passage, l' , made through the side, bottom, or top of the case C to allow the escape of water from the case, allows the descent of the valve I, on the closing of the cock, by removing the excess of pressure from beneath it. The exit-orifice l' would not be operative for the purpose stated unless the induction-pipe A were closable.

I will now describe the operation of the disk-valve E. This valve, when raised by the influx of water through pipe A, (by the opening of the cock L' in pipe L, or the cock B in pipe A,) closes against the valve-seat G^2 beneath the neck G' , and closes the openings g , which lead from the lower part, F' , of the cylinder-chamber into the circumferential groove or channel G. When these ports g are closed the water passes through the small orifice e and through the neck G' , and causes the piston H to rise. At the same time the cylinder F is lifted by the pressure of water beneath. The main body of water then flows beneath the edge of the cylinder F, and upward between the cylinder and case C, then over the upper edge of the cylinder, and through the eduction-pipe L, supplying, say, a house or factory.

The ascent of the cylinder F should be limited to prevent its upper edge coming into too close proximity to the top of the case. I provide for this by a collar, F^2 , which comes in contact with the lower guide-screws, J, when the cylinder has attained its maximum elevation. (See Fig. 2.) As the water flows through the pipe L the piston H is constantly rising in the cylinder F until the automatic valve I reaches its seat K, (unless the cock B or L' is closed before that time.) When the valve I reaches its seat the flow of water is substantially stopped by it, and no more water will flow until the cock has been again closed. On the closing of the cock the valve leaves its seat and another quantity of water can be drawn. When the discharge-pipe L is closed by the valve I the disk-valve E first drops, opening

the ports g , then the cylinder F descends, closing the passage beneath its edge. As the piston H descends the water beneath the piston escapes through the neck G' and the ports g , and flows up the annular passage F' , between the cylinder F and case C, into the top of the cylinder, as shown by arrows in Fig. 1. The piston descends to the neck G' , but the valve I remains closed against its seat until a discharge-cock, L', or a cock, B, is opened.

In Fig. 3 is shown a modification in which there is a passage, h' , through the bottom of the piston H, to allow the water to pass upward through the piston as it leaves the ball-valve and descends in the cylinder F. In this modification the ball-valve is made of sufficient weight to remain in its cup on the piston while the piston is ascending and keep the passage h' closed.

I claim as my invention—

1. The combination of case C, cylinder F, and automatic valve, composed of piston H and separable valve I, closing the eduction-pipe L.
2. In an apparatus for checking the waste of water, the combination of an automatic valve adapted to close the eduction-port of the case, and a passage for the escape of water from the case, between the induction valve or cock and the eduction-valve of the case.
3. The combination, with case C and cylinder F, containing an automatic valve adapted to close the eduction-opening of the case, of the disk-valve E, having orifice e , and closing the ports g , connecting the lower part of the cylinder with the circumferential groove.
4. In an apparatus for checking the waste of water, the combination, with the cylinder F, having seat G^2 , of the disk-valve E, with an orifice, e , and clearing-pin d , for the purpose set forth.

ELLIOTT E. FURNEY.
